UNITED STATES PATENT OFFICE.

CYRIL LAVALLE, OF WEBSTER, MASSACHUSETTS.

SHUTTLE-BOX FOR LOOMS.

1,376,949.

Specification of Letters Patent.

Patented May 3, 1921.

Application filed January 2, 1920. Serial No. 348,965.

To all whom it may concern:

Be it known that I, CYRIL LAVALLE, a citizen of the United States, residing at Webster, in the county of Worcester and

5 Commonwealth of Massachusetts, have invented a new and useful Improvement in Shuttle-Boxes for Looms, of which the following, together with the accompanying drawings, is a specification.

10 My invention relates to shuttle boxes for looms and has for its object to provide certain improvements in the mechanism shown and described in United States Letters Patent No. 1,296,697, for a loom, issued 15 to me on March 11, 1919 jointly with Arthur F. Raymond and Alphonse Mathieu.

The mechanism covered by the above described patent is associated with the picking mechanism of a loom and provides 20 means for retaining and gripping the shuttle thread each time the shuttle is sent fully "home" in the shuttle box, so that the portion of the thread projecting beyond the shuttle box is held taut and is prevented 25 from sagging and thus becoming entangled with any of the other shuttle threads of the loom.

The specific means employed to retain the thread consists of a pivotally mounted arm 30 adapted to be engaged and moved by the tapered end of the shuttle as it enters the closed end of the box. The arm is provided with a curved rack portion in mesh with a pinion which carries a rod extending to the 35 open end of the shuttle box. This rod is provided with a bent over portion which clamps the thread against the wall of the shuttle box each time that the arm and its pinion is turned by the entrance of a shuttle 40 therein. While the above described construction operates satisfactorily in principle, nevertheless the pivotally mounted arm is liable to get out of mesh with its pinion owing to the fact that no provision is made 45 for adjusting its travel. A further defect of the above described construction lies in the fact that the binders of the shuttle box must be removed in order to apply the arm and pinion thereto.

50 By my invention I propose to greatly improve the above described construction by providing a slide for turning the pinion, the amount of travel of the slide being controlled by suitable adjusting means. I further provide a separate frame for carrying 55 the several slides and pinions which is

adapted to be applied to the loom as a unit, whereby my improved device may be attached to any type of loom without making any changes in its construction. 60

In the accompanying drawings,

Figure 1 is a front view of a well known form of shuttle box having my invention attached thereto.

Fig. 2 is an end view of the box shown 65 in Fig. 1.

Fig. 3 is a sectional view along the line 3—3, Fig. 1.

Similar reference characters refer to similar parts in the different figures. 70

The invention is shown in connection with a multiple type shuttle box of a well known construction which comprises superimposed raceways 1 and 2 for the travel of a pair of shuttles 3 therein. It is obvious, however, 75 that my invention may be as well applied to a shuttle box adapted to receive any desired number of shuttles. The raceway for each shuttle 3 is formed by the back wall 4 of the box and the horizontal partitions 5 80 between the raceways, there being the usual clearance between the shuttle 3 and the front wall 6 of the box.

The front wall 6 provides bearing lugs 7 for a shaft 8, upon which are pivotally 85 mounted the swells or shuttle binders 9. The binders 9 are forced into the shuttle box by springs 10, so that as the shuttles 3 move to the right or toward the closed end of the box, the binders 9 are pressed against the 90 shuttles 3 to arrest their movement and to prevent rebound, in the usual manner. The free ends of the binders 9 are limited in their outward movement by a rod 11 carried by lugs 12 on the front wall 6. 95

A frame 13 is secured at its ends to the top and bottom partitions 5 of the box by means of set screws 14 which permit the frame to be vertically adjusted with respect to the box. The frame 13 is provided with 100 notches 15 for the reception of the ends of the partitions 5, and with substantially semicircular depressions 16 for allowing free movement of the binders 9 therein. The projecting portions of the frame 13 between 105 the notches 15 and the depressions 16 are provided with parallel openings 17 extending from the front to the rear of the frame.

A plurality of slides 18 respectively comprise a pair of parallel rods 19 adapted to 110 slide within the openings 17 and a crossbar 20 secured to the ends of the rods 19. The

rods 19 are respectively provided at their ends with a threaded portion 21 having adjusting nuts 22 in engagement therewith, and the lower rod of each slide is provided 5 with a rack portion 23. The slides 18 are adapted to be normally maintained toward the back wall 4 of the shuttle box by springs 24 which are secured to the front wall 6 beneath the binder springs 10. It is obvious 10 that any other type of spring may be employed to hold the slides in their outward position, such for example as coil springs surrounding the rods 19. The movement of each slide under the influence of the spring 15 24 is limited by the nuts 22.

The frame 13 is also provided with a plurality of openings 25 extending at right angles to the openings 17, within which are located pinions 26 each in engagement with 20 the rack portion 23 of a slide. Each pinion 26 is provided with a shaft 27 which extends parallel to the raceways and is supported at its end in a bracket 28 secured to the partition 5 at the open end of the shuttle box. 25 The shaft 27 is provided with a clamping portion 29 extending at right angles thereto, as best shown in Fig. 3.

From the foregoing it is apparent that when a shuttle 3 is driven "home" in the 30 box by reaching the end of its movement to the right the tapered end portion 30 thereof will engage the crossbar 20 of a slide 18 and force it outwardly against the action of the spring 24. As this occurs the movement of 35 the rack portion 23 turns the corresponding pinion 26 with its shaft 27, whereupon the clamping portion 29 moves upwardly and clamps the thread 31 extending from the end of the shuttle 3 against the front wall 6 of 40 the shuttle box. In this way the thread 31 is prevented from sagging downwardly or from being pulled out of place by the beating action of the fabric on the loom.

It is apparent that the several slides and 45 shafts can be assembled on the frame 13 and then applied to the shuttle box as a complete unit, it only being necessary to adjust the position of the frame by means of the set screws 14, and to attach the ends of the 50 shafts 27 by means of the brackets 28. This may be done, of course, without in any way disturbing the parts of the shuttle box. After the frame has been attached to the box, the movement of the slides 18 can be 55 adjusted to correspond to the size of the shuttle and the width of the shuttle box by means of the adjusting nuts 22. The provi-

sion of parallel bearing members on the slide insures that it will always move freely without binding, due to the fact that the force 60 of the impact of the shuttle is transmitted equally to the rods 19 by the crossbar 20.

While I have shown my invention in its simplest and preferred form, it is not so limited, but is susceptible of various modifications within the scope of the appended claims.

I claim—

1. In a loom, a frame mounted at the closed end of the shuttle box and provided 70 with means for clamping the weft thread at the open end of the shuttle box.

2. In a loom, a frame detachably secured to the shuttle box, at its closed end, and provided with a device for clamping the weft 75 thread at the open end of the shuttle box.

3. In a loom, a frame embracing the top and bottom portions of the shuttle box at its closed end and provided with a device actuated by movement of the shuttle for 80 clamping the weft thread at the open end of the shuttle box.

4. In a loom, a frame mounted at the closed end of the shuttle box and provided with a slide normally extending into the 85 path of movement of the shuttle and connected to a weft thread clamping device at the open end of the shuttle box.

5. In a loom, a frame mounted at the closed end of the shuttle box and provided 90 with a slide connected to a weft thread clamping device, and means for adjusting the position of the slide in the shuttle box.

6. In a loom, a frame mounted at the closed end of the shuttle box and provided 95 with a slide connected to a weft thread clamping device, the said slide comprising parallel members, movable within the frame, and a cross member joining the movable members and adapted to be struck by the 100 shuttle.

7. In a loom, a frame mounted at the closed end of the shuttle box and provided with an operating device yieldably held in the path of movement of the shuttle, the 105 said device comprising members slidably mounted on the frame and joined by a cross member for receiving the impact of the shuttle as it enters the closed end of the box.

CYRIL LAVALLE.
